UNITED STATES PATENT OFFICE.

JOHN J. THACHER, OF ATTLEBORO, MASSACHUSETTS, ASSIGNOR TO BROWN & SHARPE MFG. CO., OF PROVIDENCE, RHODE ISLAND, A CORPORATION OF RHODE ISLAND.

GRINDING-MACHINE.

1,176,180.

Specification of Letters Patent. Patented Mar. 21, 1916.

Application filed March 8, 1915. Serial No. 13,020.

To all whom it may concern:

Be it known that I, JOHN J. THACHER, a citizen of the United States, residing at Attleboro, in the county of Bristol and State 5 of Massachusetts, have invented certain new and useful Improvements in Grinding-Machines; and I do hereby declare the following to be a full, clear, and exact description of the invention, such as will enable others 10 skilled in the art to which it appertains to make and use the same.

The invention relates to grinding machines, and more particularly to means for controlling the speed of rotation of the 15 work, and the speed of the relative travel of the work and grinding wheel.

In the grinding machines now on the market, considerable difficulty is often experienced in obtaining the proper adjustment 20 of the mechanism for rotating the work to the relative travel of the work and grinding wheel in order to secure the best combination of speeds for effecting satisfactory results; and this is true whether the work be 25 made to travel past the grinding wheel, or whether the work rotates upon a stationary support and a corresponding relative movement of the grinding wheel be effected. To obtain the best results the speeds employed 30 should be those best suited to the character of the work, and it is highly desirable that the changes and adjustments requisite for securing such speeds should be quickly and intelligently made.

35 It is the object of the present invention to regulate and adjust independently the rate of said speeds, to render said control and adjustment readily accessible to the hand of the operator, to indicate clearly at all times 40 the number of rotations per minute of the work and the rate of the relative travel of the work and grinding wheel, to render the starting and stopping mechanisms effecting said rotations and relative travel independent of the grinding wheel mechanism, and in general to simplify the parts and combine the movements of such mechanisms in such relation as to obtain the most economical and effective results.

45 In its preferred form, the invention is embodied in a grinding machine having two independent variable speed mechanisms, one for rotating the work and the other for effecting the movement of the work longitudi-

dinally past the grinding wheel. Each of 55 said variable mechanisms is actuated by two series of friction disks, one series being mounted upon a stationary driven shaft and the other upon a movable driving shaft, and operatively in contact as is well known in 60 this type of mechanism. The controlling means employed consists of two independent concentric shafts, one of which is arranged to adjust the variable speed mechanism actuating the work; and the other of which is 65 arranged to adjust the variable speed mechanism actuating the table, each of said shafts being connected with one of two concentric dials mounted at the front of the machine, and operated by levers within convenient reach of the operator. In close proximity to said dials is also the lever connected with means for stopping and starting the said variable mechanisms.

The features of the invention will be 75 readily understood from an inspection of the accompanying drawings, and the following detailed description of the machine illustrated therein.

In the drawings, Figure 1 is an end elevation of a grinding machine embodying the invention in its preferred form; Fig. 2 is a view of the interior of the variable speed case, the back cover thereof being removed; Fig. 3 is a horizontal section of the said 85 speed case and connections taken diagonally through the bearings of the main shaft and controlling mechanism; Fig. 4 is a vertical section of the speed case, the dials and controlling mechanism; Fig. 5 is a plan view of 90 the dials, the operating handles, and the starting and stopping lever; and Fig. 6 is a vertical section of the dials shown in Fig. 5 through the operating handles thereof.

The frame 7 of the grinding machine embodying the invention is provided with the usual ways 8, movable carriage 9, table 10 carried thereon for supporting the head and footstocks, and the usual grinding wheel 11, which is suitably connected with some 100 source of power. As here shown, the carriage and table are moved longitudinally and the said grinding wheel is mounted upon a transversely movable carriage which is held against movement in a direction longitudinal of the table, but as is obvious, the movement of the table relative to said grinding wheel could also be accomplished by 105

having the table stationary and effecting a corresponding travel of the grinding wheel carriage.

The variable speed mechanisms for rotating the work and for effecting the longitudinal feeding movement of the table is contained in the case 12 which is located at the rear of the machine and is normally closed by the cover 13. Within the case 12, 10 the shaft 14 is journaled in suitable bearings secured within the walls thereof, and is connected to the pulley 15, which is located on the outside of said case and is connected with some suitable source of power 16 by 15 the belt 17. Connected with said shaft 14 by means of the swinging bearings 18 and 19 is the countershaft 20 carrying the friction disks 21 and the gear 22, which meshes with the gear 23 carried upon the shaft 14 20 and is operated thereby. Similarly connected to the shaft 14 by means of the swinging bearings 24 and 25 is the shaft 26 carrying thereon the friction disks 27 and the gear 28, which meshes with the gear 29 mounted 25 upon the shaft 14 and is operated thereby.

The work is rotated by means of the pulley 41 adjacent thereto, which is connected by the belt 40 to the pulley 39 which is mounted upon the shaft 38 located above 30 the machine. Upon said shaft 38 is also mounted the pulley 37 which is connected by a belt 36 to the pulley 35 mounted upon the end of the shaft 30 outside of the case 12. Upon the shaft 30 journaled in suitable 35 bearings in the lower portion of the walls of the case 12 are the friction disks 31, engaging with the series of friction disks 27 in the manner well-known in the art, and being free to move longitudinally upon the square portion 32 of the shaft 30. The series of friction disks 27 and 31 are kept in close engagement by means of the movable sleeve 33 actuated by the spring 34.

The usual mechanism is employed for effecting the longitudinal movement of the table and is connected by means of the chain 86 to the sprocket 47 mounted upon one end of the shaft 42, which is mounted in suitable bearings in the wall of the upper portion of the case 12. The shaft 42 carries upon the square shaft portion 43 thereof the friction disks 44 which are operatively in contact with the friction disks 21 and are held in close engagement therewith by 50 means of the movable sleeve 45 and the spring 46. For the purpose of stopping and starting each of the said mechanisms for rotating the work and moving the table, there is pivotally mounted on the rear wall of the 55 case 12 the lever 48, the arms 49 and 50, which carry the blades 51 and 52 respectively, the blade 51 engaging with the annular flange 53 upon the sleeve 45, and the blade 52 engaging with the annular flange 54 upon the sleeve 33, and each of said

sleeves having respectively the disks 82 and 83 integral therewith, and arranged to engage respectively with the brakes 84 and 85. Upon sufficient pressure being exerted by said blades upon the said flanges, the pressure of the said helical springs upon the sleeves will be stopped, thereby releasing the close engagement of the frictional disks which have been operatively in contact, and at the same time the disks 82 and 83 integral 75 with said sleeves will be brought in contact with the brakes adjacent thereto, thereby stopping further rotation of the shafts 42 and 30. Also connected with said lever 48 is the arm 55 having therein the groove 80 56 engaging with the finger 57 mounted upon a rocking shaft 58 journaled in suitable bearings, one of which is located in the rear wall of said box (see Fig. 2), and the other of which is connected with the bracket 85 70 (see Fig. 6). The shaft 52 is actuated by a hand lever secured thereto in close proximity to the handles controlling the dials hereinafter described and within convenient reach of the left hand of the operator. Also 90 located within the case 12, is the mechanism for changing and adjusting the relative positions of the movable driving and the driven shafts. Mounted upon the main shaft 14 is the yoke 62 which is also connected 95 through the swinging bearings 18, 19 to the shaft 20 and mounted upon said yoke 62 at one side thereof is the gear segment 60 which meshes with the beveled gear 64, mounted upon the central shaft 65. Also 100 mounted upon said shaft 14 is the yoke 63 which is also connected through the swinging bearings 24, 25 to the shaft 26, and mounted upon said yoke 63, at one side thereof, is the beveled gear segment 61 which 105 meshes with the beveled gear 66 carried by the hollow shaft 67.

For controlling and varying the speeds from the front of the machine, concentric shafts 65 and 67 are employed. The hollow shaft 67 is mounted within the sleeve 68, one end of which is secured to the case 12 by means of the socket 69, and the other end of which is secured to the bracket 70, which is mounted upon the face of the main 110 frame. The hollow shaft 67 is connected with the collar 71 which is secured to the hub of the dial 72 turned by the handle 73 marked "Head". The shaft 65 is keyed to the hub 74 of the dial 75, the said dial being 115 concentric with the dial 72 and turned by the handle 76 marked "Table".

In order to provide the operator with a ready means for ascertaining the speed of rotation of the work and the speed of the longitudinal travel of the table, a scale is provided upon the face of each dial, the figures of dial 72 indicating the available speeds in revolutions per minute for the rotation of the work, and the figures of dial 75 in- 120 125 130

dicating the available speeds in inches per minute for the longitudinal movement of the table, and a double pointer 81 being carried upon the rim 78 of the disk 77, which is located between the said dials and which is integral with the bracket 70 and thereby secured against rotation. For the purpose of holding the parts securely in any adjusted position, the rim 78 is provided upon opposite sides with the teeth 79 and 80 which are engaged by spring pressed detent pawls 79' and 80' mounted respectively in the adjusting dials 72 and 75. To prevent accidental displacement of the adjusting dials 10 the pawls are normally locked in engagement with the teeth. As shown, the pawl 79' is thus locked by a spring pressed locking pin 73', to the outer end of which the handle 73 is secured. The inner end of the pin is provided with a flange bearing against the detent pawl 79', and is also provided with a projection which extends back of the rear end of the detent and locks it in engagement with the teeth 79 until the operator draws 20 the handle 73 outward, preparatory to adjusting the dial 72 and connected parts. The detent pawl 80' is normally locked in position by a similar spring pressed locking pin 76', to the outer end of which the handle 76 is secured. The pin 76' is provided with 25 a flange bearing against the detent pawl 80', and with a projection extending into a slot in the pawl and locking it in position until the operator draws the handle 76 outward, 30 preparatory to adjusting the dial 75 and connected parts.

As will be observed, the movement of the handle 73 actuating the hollow shaft 67 will be communicated through the connecting 35 gears to the driving shaft 26, and will cause the same to swing upon its bearings 24 and thereby to control the speed of rotation of the work, and also the movement of the handle 76 will cause a corresponding movement of the shaft 65, which will also be communicated through the connecting gears to the driving shaft 20, and will cause the same to swing upon its bearings 18 thereby controlling the feed of the table.

50 It will thus be seen that if for any reason the operator desires to move the table more rapidly, or to decrease such speed, he can very easily accomplish this by means of the proper adjustment of the handle 76, and also if he desires for any reason to increase or diminish the speed of rotation of the work, this can be readily accomplished by the proper movement of the handle 73. By co-ordinating the two speeds, it is thus apparent 55 that the proper combination can be very quickly and readily secured. The right hand of the operator is left free, and all adjustments of the handles are quickly and readily accomplished by the use of the left hand of 60 the operator, as well as the adjustment of the

lever 59, which is also in close proximity to the handles of the dials, and which permits the driving mechanism to be instantly stopped or started without affecting the grinding wheel. There is no complication 70 about the operation of this controlling mechanism, and the use of the same, even in the hands of a comparatively inexperienced operator, increases the output by reducing setting-up time, by making correct speed and 75 feed combinations quickly available, and by providing for rapid changes for different diameters on the same piece.

The preferred mode of operation is as follows: After the work has been duly placed 80 into operative position upon the head and foot stocks, the handles 73 and 76 are carefully adjusted to the character of the work, and both the variable mechanisms are started by turning the lever 59. Prior to this, the 85 grinding wheel mechanism should also have been carefully adjusted and started, and should ordinarily be kept running during the entire operation, it being independent of both the variable speed mechanisms and not 90 needing to be stopped when they are stopped or adjusted. Should it be found that further adjustments of the speeds are necessary or desirable, such adjustments can be readily made and correct speed combinations quickly 95 effected. Upon completion of the grinding operation, or during any stage thereof, the variable mechanisms may be stopped at any time by the hand lever 59.

While it is preferred to employ the specific construction and arrangement of parts shown and described, it will be understood that this construction and arrangement is not essential to the broader features of the invention, and may be varied or modified as 105 found desirable or best suited to the construction of the machine in which the invention is to be embodied.

Having explained the nature and object of the invention, and specifically described 110 one form of mechanism in which it may be embodied, what is claimed is:—

1. A grinding machine, having, in combination, feeding mechanisms for effecting the travel of the work and grinding wheel relative to each other, mechanism for rotating the work, and adjusting devices arranged adjacent to each other within convenient reach of the operator and operatively connected to said mechanisms to independently 115 vary the feed and the speed of rotation of the work.

2. A grinding machine, having, in combination, feeding mechanism for effecting at 120 variable speeds the travel of the work and grinding wheel relative to each other, mechanism for rotating the work at variable speeds, and manually controlled adjusting devices mounted to turn about a common axis within convenient reach of the opera- 125 130

- tor and operatively connected with said mechanisms for independently adjusting each of said variable speeds through the mechanism controlling the same.
5. A grinding machine, having, in combination, feeding mechanism for effecting at variable speeds the travel of the work and grinding wheel relative to each other, mechanism for rotating the work at variable speeds, two concentric shafts, and means at the forward ends of said shafts within convenient reach of the operator for manually adjusting the same, each of said shafts being operatively connected at its rear end with one of said mechanisms and controlling the said variations of speed actuated thereby.
20. A grinding machine, having, in combination, feeding mechanism for effecting at variable speeds the travel of the work and grinding wheel relative to each other, mechanism for rotating the work at variable speeds, two independently operated concentric shafts, and two concentric dials at the forward ends of said shafts within convenient reach of the operator for manually adjusting said shafts, each of said shafts being operatively connected at its rear end with one of said mechanisms and controlling the said variations of speed actuated thereby.
25. A grinding machine, having, in combination, feeding mechanism for effecting at variable speeds the travel of the work and grinding wheel relative to each other, mechanism for rotating the work at variable speeds, two independently operated concentric shafts, two concentric dials, each of which is mounted upon the forward end of one of said shafts and movable therewith and serving to adjust the same, a stationary dial located between said movable dials and concentric therewith, the rear of each shaft being operatively connected at its rear end with one of said mechanisms and controlling the same, and said dials being within convenient reach of the hand of the operator.
30. A grinding machine, having, in combination, mechanism for effecting the travel of the work and grinding wheel relative to each other, mechanism for rotating the work, two independent mechanisms, one for varying the speed of said relative travel of the work and grinding wheel and the other for varying the speed of rotation of the work, a gear segment operatively connected to adjust each of said independent mechanisms and controlling the variable speed produced by the same, two concentric shafts, and a gear at the end of each of said shafts meshing with one of said gear segments and serving to operate the same.
35. A grinding machine, having, in combination, friction disk mechanism for effect-

ing the relative travel of the work and grinding wheel at variable speeds, friction disk mechanism for rotating the work at variable speeds, and manually controlled means rotating about a common axis within 70 convenient reach of the operator and operatively connected with said mechanism for independently adjusting the same.

8. A grinding machine, having, in combination, friction disk mechanism for effecting the relative travel of the work and grinding wheel, friction disk mechanism for rotating the work, each disk mechanism having a movable driving shaft and a fixed driven shaft and friction disks carried upon 80 each of said shafts and operatively in contact, a gear segment operatively connected to adjust each of said movable driving shafts, two independently operated concentric shafts, and a gear at the rear end of 85 each of said shafts meshing with one of said gear segments and serving to operate the same.

9. A grinding machine, having, in combination, friction disk mechanism for effecting 90 the relative travel of the work and grinding wheel, friction disk mechanism for rotating the work, each disk mechanism having a movable driving shaft journaled in swinging bearings and a fixed driven shaft and 95 friction disks carried upon each of said shafts and operatively in contact, a gear segment operatively connected to each of said swinging bearings, two independently operated concentric shafts, a gear at the rear end 100 of each of said shafts and meshing with one of said gear segments and serving to operate the same, and means within convenient reach of the operator for manually controlling the rotation of said shafts.

10. A grinding machine, having, in combination, friction disk mechanism for effecting the relative travel of the work and grinding wheel, friction disk mechanism for rotating the work, each disk mechanism having a movable driving shaft and a fixed driven shaft and friction disks carried upon each of said shafts and operatively in contact, a gear segment operatively connected to adjust each of said movable driving shafts, 110 two independently operated concentric shafts, a gear at the rear end of each of said shafts and meshing with one of said gear segments and serving to operate the same, a lever for stopping and starting the operation of said disk mechanism, and means within convenient reach of the operator for manually controlling said lever and the rotation of said shafts.

11. A grinding machine, having, in combination, friction disk mechanism for effecting the relative travel of the work and grinding wheel, friction disk mechanism for rotating the work, each disk mechanism having a movable driving shaft and a fixed 125

130

driven shaft and friction disks carried upon each of said shafts and operatively in contact, a gear segment operatively connected to adjust each of said movable driving shafts, 5 two independently operated concentric shafts, a gear at the rear end of each of said shafts and meshing with one of said gear segments and serving to operate the same, a lever for stopping and starting the operation 10 of said disk mechanism, concentric dials on the forward ends of said shafts for controlling the rotation of the same, and a handle operatively connected with said lever and in close proximity with said dials at the front 15 of the machine, whereby all the said controlling means for operating the machine are within convenient reach of the operator.

12. A grinding machine, having, in combination, variable feeding mechanism for effecting the travel of the work and grinding wheel relative to each other, variable mechanism for rotating the work independent of said feeding mechanism, manually controlled means operatively connected with said mechanisms for adjusting the same, and coöperating scales indicating the revolutions per minute of the work and the rate of feed in inches per minute.

13. A grinding machine, having, in combination, feeding mechanism for effecting at variable speeds the travel of the work and grinding wheel relative to each other, mechanism for rotating the work at variable speeds and manually controlled adjusting 35 devices mounted to turn about a common axis within convenient reach of the operator, and operatively connected with said mechanisms for independently adjusting each of said variable speeds through the mechanism 40 controlling the same, and coöperating scales indicating the revolutions per minute of the work and rate of feed in inches per minute.

14. A grinding machine, having, in combination, feeding mechanism for effecting at 45 variable speeds the travel of the work and grinding wheel relative to each other, mech-

anism for rotating the work at variable speeds, two independently operated concentric shafts and two concentric dials at the forward ends of said shafts within convenient reach of the operator for manually adjusting said shafts, each of said shafts being operatively connected at its rear end with one of said mechanisms and controlling the said variations of speed actuated thereby, 50 one of said dials indicating the number of revolutions per minute of the work and the other dial indicating the rate of feed in inches per minute.

15. A grinding machine, having, in combination, feeding mechanism for effecting at variable speeds the travel of the work and grinding wheel relatively to each other, mechanism for rotating the work at variable speeds, two concentric shafts, means at the 65 forward ends of said shafts within convenient reach of the operator for normally locking them in position and for manually releasing and adjusting the same, and means at the rear ends of the shafts for connecting 70 them respectively with the variable speed mechanisms.

16. A grinding machine, having, in combination, feeding mechanism for effecting at variable speeds the travel of the work and 75 grinding wheel relative to each other, mechanism for rotating the work at variable speeds, two concentric shafts having their rear ends connected respectively with said mechanism, two concentric dials on the forward ends of the shafts, a stationary rim between the dials provided with teeth on its opposite sides, spring pressed detent pawls mounted in the dials to engage the teeth, and spring pressed locking pins for the pawls 80 provided with operating handles at their outer ends.
